UNITED STATES PATENT OFFICE.

FREDERICK P. ROSBACK, OF CHICAGO, ILLINOIS, ASSIGNOR TO WILLIAM P. HEALY, OF SAME PLACE.

BOX NAILING AND PRINTING MACHINE.

SPECIFICATION forming part of Letters Patent No. 608,917, dated August 9, 1898.

Application filed December 7, 1897. Serial No. 661,031. (No model.)

To all whom it may concern:

Be it known that I, FREDERICK P. ROSBACK, a citizen of the United States, residing at Chicago, in the county of Cook and State of Illinois, have invented a new and useful Improvement in Box Nailing and Printing Machines, of which the following is a specification.

This invention relates to box-nailing machines generally, and more especially to an improved machine for use in the construction of wire-bound packing-boxes to fasten the ends of the boxes in place by nailing them to the end reinforcing-cleats. The machine is also provided with printing mechanism, whereby advertisements may be printed upon the ends of the boxes.

My object is to provide a machine of generally-improved construction, adapting it more especially for fastening the sides and bottom to the ends in the construction of wire-bound boxes, whereby the operation may be performed with economy in time and labor. The wire-bound box referred to consists of a sheet in one or more sections, reinforced on one side with cleats and at its opposite side with strengthening-wires, the sheet and wires being fastened with staples to the cleats, and the blank thus formed being step-mitered and bent at the step-miter cuts to form the top, bottom, and sides of the box. A wire-bound box is shown in perspective in Figure 37. These boxes may be of any size and shape and are particularly desirable on account of their strength and lightness.

My invention is not to be limited to the use of printing mechanism in combination with the box-nailing mechanism, because my primary object is to provide a machine which will drive nails at three edges of the box end in one operation, and the printing of the box ends, though very desirable in many instances, is a secondary object.

In the drawings, Fig. 1 is a side elevation of my improved box nailing and printing machine; Fig. 2, an elevation of the opposite side of the machine; Fig. 3, a rear end elevation thereof; Fig. 4, a vertical section taken on line 4 of Fig. 1; Figs. 5, 6, and 7, enlarged broken sections taken on lines 5, 6, and 7 of Fig. 2; Fig. 8, an enlarged broken section

taken on line 8 of Fig. 5; Fig. 9, a broken plan section taken on line 9 of Fig. 8; Fig. 10, a broken section taken on line 10 of Fig. 9 and showing details of clutch mechanism; Figs. 11 and 12, sections taken, respectively, on lines 11 and 12 of Fig. 10; Fig. 13, an enlarged sectional detail view of another clutch mechanism, the section being taken on line 13 of Fig. 9; Fig. 14, an enlarged and broken section taken on line 14 of Fig. 5 and illustrating the construction of one of the nail-drivers; Fig. 15, a section taken on line 15 of Fig. 14; Fig. 16, a section taken on line 16 of Fig. 5; Fig. 17, an enlarged broken view, partly in section and partly in side elevation, illustrating nail-feeding mechanism; Fig. 18, a broken sectional view taken on line 18 of Fig. 17; Fig. 19, a broken section taken on line 19 of Fig. 18; Fig. 20, a broken view showing sections taken on the lines 20 20 of Fig. 19; Fig. 21, a broken view, partly plan and partly sectional, the section being taken on line 21 of Fig. 19; Fig. 22, a broken section illustrating details of construction of the parts illustrated in Figs. 17 to 21, inclusive; Figs. 23, 24, and 25, broken sectional plan views taken on lines 23, 24, and 25 of Fig. 17; Fig. 26, a sectional view illustrating box-end-feeding mechanism, the section being taken on line 26 of Fig. 29; Fig. 27, an enlarged broken sectional view taken on line 27 of Fig. 6; Fig. 28, a sectional view, also taken on line 27 of Fig. 6 and in the nature of a continuation of Fig. 27; Fig. 29, a sectional plan view taken on line 29 of Fig. 27; Fig. 30, an enlarged section taken on line 30 of Fig. 27; Fig. 31, a section taken on line 31 of Fig. 30 and illustrating the nail feeding and positioning mechanism and the manner in which a nail is driven and clenched; Fig. 32, a section taken on line 32 of Fig. 31; Fig. 33, a broken section taken on line 33 of Fig. 31; Fig. 34, a broken section taken on line 34 of Fig. 27 and showing a box end in position to receive the sides of the box; Fig. 35, a view, the same as Fig. 34, showing the sides of a box folded upon the box end ready for the nailing operation; Fig. 36, a broken plan section taken on line 36 of Fig. 34, and Fig. 37 a perspective view of a completed wire-bound box.

In each instance sectional figures are to be viewed in the direction of the arrows at the lines on which the sections are taken.

A is the frame of the machine, formed with 5 side frames or cheeks A' A², mounted upon feet A³, rear end A⁴, cross-braces A⁵, and forward cheek extensions A⁶ A⁷, having legs A⁸.

B is the drive-shaft, provided with a pulley B', which is belted to a pulley on a line-shaft 10 or the like to rotate and turn the shaft B constantly. Fixed to the shaft B is a pinion B². Journaled in the cheeks above the shaft B is a counter-shaft C. On the shaft C are two fixed collars C' C², and between the collars is 15 a gear-wheel C³, having a hub C⁴, which is normally loose upon the shaft C. The gear-wheel C³ meshes with the pinion B² and rotates constantly, but being normally loose upon the shaft C the latter is normally at 20 rest.

In the shaft C (see Figs. 10, 11, and 12) is a longitudinally-extending concave recess t of a length which causes it to extend beneath the collars C' C² and hub C⁴. Resting in the 25 recess t is a rocking clutch-pin t', provided at one end with a laterally-extending arm t², having a cam edge t³ and stop projection t⁴. In the collar C' is a radial recess t⁵, through which the arm t² extends, and in the said recess and connected at one end with the arm t² and at its opposite end to the collar is a spring t⁶. The pin t' is cylindrical at the ends; but between the ends, where it passes through the hub C⁴, it is half-round, being formed so 30 by a recess t⁷ in the pin. The spring t⁶ tends to draw the arm t² and rock the pin to the position indicated in Fig. 12, whereby it will engage one of two recesses or notches t⁸ in the inner circumference of the hub C⁴. When 35 the arm t² is in the position indicated in Fig. 11, the pin t' is rocked to the left from the position shown in Fig. 12, whereby the half-round portion of the pin is altogether in the recess t of the shaft, and the hub will move 40 over it without being engaged by the pin. In other words, when the parts are in the position shown in Fig. 11 the gear-wheel C³ rotates loosely upon the shaft C, and when the parts are in the position shown in Fig. 12 the 45 shaft C is locked to the gear-wheel C³ and rotates therewith. Fulcrumed at t⁹ on the cheek A' is a lever t¹⁰, connected by a rod t¹¹ with a bell-crank lever t¹², held normally in the position shown in Fig. 1 by a spring t¹³. 50 Connected at its lower end with an arm of the bell-crank lever is an upward-extending rod t¹⁴. (See Fig. 11.) A lever t¹⁵, fulcrumed between its ends on a bracket t¹⁶ at the cheek A', is pivotally connected at one end to the 55 rod t¹⁴ and at its opposite end carries a downward-projecting lip t¹⁷, which in the rotation of the collar C' rides upon the circumference thereof and tends to engage the projecting end portion t¹⁸ of the arm t². 60 In the operation of the machine the intention is to cause the shaft C to be given one complete revolution and then stop. Thus

when it is desired that the shaft C and attendant parts shall rotate the handle t¹⁹ is moved by the operator to the left in Fig. 1 to 70 swing the bell-crank lever t¹² against the resistance of the spring t¹³ and draw down the rod t¹⁴, whereby the lever t¹⁵ is turned to lift the lip t¹⁷ out of engagement with the arm t². This permits the spring t⁶ to rock the pin t' on 75 its axis as soon as a recess t⁸ registers therewith, whereby it will project into the recess t⁸ and lock the shaft C to the rotating gear-wheel C³. The handle t¹⁹ is then immediately released by the operator, whereby the spring t¹³ exerts itself to press the stop t¹⁷ upon the 80 circumference of the collar C'. Thus when the shaft C and collar C' have nearly completed a revolution the lip t¹⁷ engages the arm t² and swings it to the position shown in 85 Fig. 11 just as the shaft has completed a revolution, thereby releasing the shaft from the rotating gear C³.

In the cheeks A' A² are coincident horizontal cross-head guide-openings s for a cross-head or ram D, having a vertical face-plate D'. Extending through the ram D and beyond the guides s is a shaft D². On the shaft C and keyed to opposite ends thereof are disks C⁵ C⁶, with which pitmen C⁶ are eccentrically connected. At their opposite ends the pitmen are pivotally connected to the end of the shaft D², whereby in each revolution of the shaft C the ram is plunged forward and back in the guides s. 90

E is an intermediate gear-wheel mounted upon a counter-shaft E', journaled in a bearing-sleeve A⁹, Fig. 9, secured upon or cast integral with the cheek A'. The gear-wheel E meshes with the gear-wheel C³, whereby it 95 rotates constantly.

F is a counter-shaft journaled at opposite ends in the cheeks A' A². Rigid upon the shaft F are collars F' F², and confined between the collars and normally loose upon the shaft is a gear-wheel F³, meshing with the gear-wheel E and rotated constantly thereby. Extending beneath the collars F' F² and gear-wheel F³ is a groove or recess r in the shaft F, (see, for example, Fig. 13,) and resting in 100 the said groove is a clutch-pin r', in all respects like the clutch-pin t', before described, and provided with a projecting arm r², extending through a radial recess r³ in the collar F' and projecting beyond the circumference of said collar. When the parts are in the position shown in Fig. 13, the gear-wheel F³ turns loosely on the shaft F, and when the pin r' is rocked to the right by the spring r⁴ the clutch-pin locks the gear-wheel and shaft 105 together, whereby the shaft is rotated by the gear-wheel. A lever r⁵ is pivoted upon a pin r⁶, which projects inward from the cheek A'. On one end of the lever r⁵ is a downward-projecting lip r⁷, and the lever is held down by 110 a spring r⁸ (see Fig. 5) to press at its lip normally upon the circumference of the collar F' to engage the projecting arm r². On the opposite end portion of the lever r⁵ is an up- 115

ward-projecting arm r^9 , held normally in an upright position against the stop r^{10} by a spring r^{11} . The arm r^9 extends normally upward into the path of a trip or cam r^{12} , carried by the cross-head or ram D, as shown in Fig. 8. The spring r^{11} is weak as compared with the spring r^8 . In the initial or forward movement of the ram D the cam r^{12} at its under surface engages the arm r^9 and swings it backward against the resistance of the spring r^{11} until it is passed by the cam. It then assumes its normal position against the stop r^{10} . In the return or backward movement of the ram the cam r^{12} at its under surface engages the arm r^9 , and as the latter is pressed against the stop r^{10} it yields in the downward direction under the cam, swinging the lever r^5 to disengage the lip r^7 from the arm r^2 of the clutch-pin. The hub of the gear-wheel F³ is provided on its inner circumference with recesses like the recesses t^8 , (shown in Fig. 12,) whereby when the arm r^2 is released by the lip r^7 the pin is turned by the spring r^4 into one of said recesses to clutch the shaft F to the gear-wheel F³ and cause the former to rotate. Before the shaft has completed a revolution the arm r^9 is released by the cam r^{12} and the lever r^5 is pressed down by the spring r^8 , whereby the lip r^7 will catch the projecting arm r^2 and rock the pin to the position of disengaging the shaft F from the gear-wheel F³. Thus in each operation the shaft F is given one complete revolution.

It will be understood from the above description that when the operator turns the handle t^{10} the drive-shaft B is given one complete revolution and then stopped. In this revolution the ram D is moved first in the forward direction and then back to its initial position. As the shaft B nears the completion of its revolution the cam r^{12} on the ram D turns the clutch mechanism on the shaft F, whereby the said shaft and attendant parts are given a complete revolution and then stopped. The movement of the shafts B F are thus intermittent, and the movement of the shaft F follows that of the shaft B, starting just before the stoppage of the latter.

Journalled in the cheek extensions A⁶ A⁷ are parallel horizontal shafts q q' , (see Figs. 28 and 29,) each carrying a pair of laterally-adjustable sprocket-wheels q' , over which run feed-chains q^2 , carrying stops or feed projections q^3 q^4 . On the cheek extensions is a receptacle for box ends X, comprising a floor or base-plate p , a stationary side plate p' , and a vertical back plate p^2 . Adjustable laterally upon the base-plate p is a vertical guide-plate p^3 . (See Fig. 26.) The feed-chains q^2 slide upon the base-plate p , and on the said base-plate are longitudinally-extending cleats p^4 , on which the box ends X rest out of contact with the chain and in position, whereby the lower box end will be engaged by a stop q^3 and moved from beneath the rest of the pile. Beneath the plate p^2 is an opening partly closed by an adjustable plate p^5 ,

which may be adjusted in accordance with the thickness of the box end and fastened in place by thumb-screws p^6 . The opening between the plate p^5 and base p is thus rendered just large enough to permit one box end and no more to pass through at a time.

G is a printing device which, as shown in the drawings, is capable of printing in two colors. It comprises two rollers n , mounted at opposite ends in the cheek extensions, with the highest points of their circumferences in the plane of the cleats or guides p^4 . Above the rollers n are printing-cylinders n' . Above the printing-cylinders n' are ink-troughs n^2 and inking-rollers n^3 . The rollers n are journaled in boxes which rest upon adjusting-screws n^4 , whereby the distance between them and the cylinders may be regulated in accordance with the thickness of the box ends. On the left-hand side of the machine, beyond the cheek extension A⁷, the shafts of the rollers n n' carry gear wheels and pinions n^5 , (see Fig. 2,) which mesh with each other, the lower two gears meshing with a gear-wheel on a shaft m , journaled on the cheek A⁷. The shaft m also carries sprocket-wheels m' m^2 . The sprocket-wheel m' is geared to a sprocket-wheel F⁴ on the shaft F by means of a drive-chain m^3 . The sprocket-wheel m^2 is geared to a sprocket-wheel q^4 on the rear shaft q by means of a drive-chain m^4 . Thus each time the shaft F is rotated the feed-chains q^2 move to advance a box end into the printing-machine, and the rollers and cylinders of the printing-machine are rotated to print upon the box end.

By providing the two printing mechanisms the box ends may be printed in two colors with suitable advertisements, the feed-chains and printing-cylinders being so geared with relation to each other that the impressions will be suitably placed upon the box ends.

In the face-plate D' of the ram D, toward the upper and lower ends thereof, are horizontal T-grooves l . Fitting against the face-plate are vertical nail-drive-attaching bars D³ D⁴, provided at the slots l with laterally-extending ends l' , through which extend nut-bolts l^2 . (See, for example, Fig. 16.) The bars D³ D⁴ may be adjusted laterally and tightened in adjusted position by means of the nut-bolts l^2 , the heads of which engage the T-slots l , as indicated. In the bars D³ D⁴ are longitudinal T-grooves l^3 .

H H' are nail-drivers, which at their ends are held in socket-pieces H². The socket-pieces H² are split and tapering, as shown in Fig. 16, and provided on their outer sides with threads to receive nuts H³, which when screwed in one direction clamp the drivers firmly in the sockets and when unscrewed loosen the hold of the socket-pieces upon the drivers, whereby the latter may be removed. The socket-pieces H² of the drivers H have threaded shanks l^4 , terminating in bolt-heads l^5 , and on the shanks are jam-nuts l^6 . The bolt-heads and shanks fit the T-grooves l^3 of

the bars D³ D⁴ and may be slid therein to any desired position and tightened in place by means of the jam-nuts l⁶. The socket-pieces which hold the drivers H' are provided with shanks l⁷, which screw into blocks H⁴, having ears l⁸, through which pass nut-bolts l⁹, the heads of which slide in the T-grooves l.

As hereinabove described, the nailing operation is performed along three edges only of a wire-bound box, being at the sides and base thereof only. The drivers H are upon the bars D³ D⁴, and the drivers H' are at the upper T-groove l, between the bars D³ D⁴. In Fig. 5 three drivers H are shown at each side and three drivers H' at the top.

It will be understood that the number of drivers may be increased as desired.

I is a pan or reservoir for nails, hinged at its lower forward corner to the tops of the cheeks A' A². On the under side of the reservoir I, at opposite sides, are ears k, to which are pivoted downward-extending rods k', pivotally connected at their lower ends with bell-crank levers k² k², secured between their ends to a rock-shaft k⁴, journaled in the cheeks A' A². The other arms of the bell-crank levers are pivotally connected to rods k³, which at their opposite ends are pivotally connected with the sides of the ram D. Thus in the reciprocation of the ram the reservoir I is swung up and down upon its hinge between the positions shown by full lines in Fig. 17 to the position indicated by the dotted lines in that figure. The base I' of the reservoir I is corrugated, as indicated most clearly in Figs. 23 and 24, longitudinal slots i being provided between the corrugations. In the forward part of the reservoir is an inclined false bottom I², which extends from the forward wall I³. The false bottom I² has a corrugated and serrated edge i', which conforms to the corrugated base I' and is slightly fluted at the ends i² to permit a nail-head to pass beneath it when the shank of the nail extends through the respective slot i, as indicated in Fig. 17.

The openings afforded by the ends i² will not permit a nail-head to pass through unless the shank thereof extends down through the respective slot i. Extending between the cheeks at the forward edge of the reservoir I is a stationary cross-brace I⁴, and at the forward upward edges of the cheeks in the position shown is a cross bar or brace I⁵, L-shaped in cross-section, as shown in Fig. 19. Above the cross-bar I⁵ in the position shown is a cross-bar I⁶. Fastened against the under side of the bar I⁶ are a series of V-shaped deflectors I⁸, forming between them a series of nail-receiving slots i³. Extending from the deflectors to the bar I⁴ are a series of slats i⁴, having openings between them which register with the openings i in the base I' of the nail-reservoir. Extending over the slats i⁴ is a plate i⁵ close enough to the slats to permit the heads to pass flatwise down the slats and prevent the nails from jarring out.

I' is a longitudinally-sliding bar resting

upon the L-shaped bar I⁵ and provided with a series of vertical openings i⁶, cutting through the rear face of the plate. Extending over the sides of the openings on the rear face of the plate are separating fingers or stops i⁷. (See, for example, Figs. 20, 21, and 22.) In the bar I⁵ and registering with the slots i³ are openings i⁸, at the lower ends of which are short tubes i⁹. Fulcrumed at i¹⁰ on the cheek A² is a lever I⁹, connected at one end to the sliding bar I⁷. The lever is cam-shaped, as shown in Fig. 18, to afford the cam-surfaces i¹¹ i¹² at opposite sides of the fulcrum i¹⁰. The bell-crank lever k², as before mentioned, is upon the shaft k⁴, which passes through the cheek A² and carries at its outer end an arm i¹³, which slides along the cam-surfaces i¹¹ i¹² of the lever I⁹. In the movement of the ram D in the forward direction—that is to say, in the direction to the right in Fig. 2—the plate or bar I⁷ is moved to the position shown in Fig. 22, whereby the nails Y in the slots i³ will move by gravity against the surface of the plate or bar, as shown in Fig. 22. In the movement of the ram in the backward direction—that is to say, to the left in Fig. 2—the fingers or stops i⁷ pass between the first and second nail in each slot i³ and in the further movement of the bar direct the first nails into the openings i⁶ as the said openings register with the openings i⁸, whereby the nails drop into the tubular extensions i⁹. Thus in the movement of the ram the reservoir I is agitated to distribute the nails in the guide-slots in the base I'. The nails rest in the said slots, being prevented from passing downward in any other position by the false bottom I². The nails pass from the openings i to the openings between the slats and are positioned by the V-shaped deflectors I⁸ in the slot i³, and in each reciprocation of the plate or bar I⁷, brought about by the reciprocation of the ram, a nail is fed from each slot i³ to a tube extension i⁹.

Extending between the cheeks A' A² is a cross-bar A¹⁰, (see Figs. 6 and 27,) provided in its upper surface with a longitudinal T-slot h. On the cheek A² in the position shown is an upright standard A¹¹, (see Figs. 2 and 6,) firmly secured in place. On the top of this standard is a transverse bar A¹², also rigid with the frame. On the bar A¹² are upward-extending brackets A¹³ A¹⁴, forming bearings for a horizontal shaft K. The bar A¹² is provided with a longitudinal slot h'. (See Fig. 27.)

K' is a vertical bar provided at its lower end with a bolt fitting the T-slot h and at its upper end with a bolt which passes through the slot h' in the bar A¹². By means of these bolts the upright bar K' may be moved toward or away from the standard A¹¹ and fastened in place to the bars A¹⁰ A¹².

L L' (see Fig. 6) are nail holders and guides. The guides L are provided with half-dovetailed flanges g, (see Fig. 30,) which engage half-dovetailed slots g' in the standard A¹¹.

and upright bar K'; also, on the nail-holders L are flanges g², through which extend thumb-screws g³, which tighten against the bars to hold the parts in adjusted position. Extending through the holders are horizontal openings g⁴, to which extend inclined openings g⁵. Extending from the openings g⁵ are tubes g⁶. The tubes g⁶ may be made of any number of interfitting or telescoping sections and extend to each one of the tube extensions i⁹, before described. The nail-holders L' are formed like the nail-holders L, but are provided with upright extensions g⁷, (see Fig. 27,) which engage the bar A¹² and are rigidly secured thereto in any adjusted position by means of thumb-screws g⁸. The drivers H H' are positioned upon the ram to drive nails in proper position with relation to the size of the box to be made, and the nail-holders L' are so adjusted in position that the drivers H H' in the forward movement of the ram will enter the openings g⁴. When a nail drops into a tube extension i⁹ and tube g⁶, it falls by gravity into a nail-holder L or L' and lies in the opening g⁴. When a driver enters the opening g⁴, it forces the nail in the direction to the right in Fig. 31 out of the opening g⁴. At the forward ends of the openings g⁴ are spreading guides g⁹ g⁹, held normally together by leaf-springs g¹⁰ on the sides of the holders. (See Fig. 32.) The guides g⁹ afford between them an opening g¹¹, just large enough to receive the shank of a nail to be driven, said opening being flared toward the opening g⁴, whereby a nail as it passes from the latter opening is guided into the opening g¹¹, and thus positioned at the point in the driving operation. The driver passes through the opening g⁴ and spreads apart the guides g⁹ to force the head into the surface of the material to be nailed. In the bar I⁶ (see Figs. 19 and 20) are thumb-screws i¹⁴, which register with the slots i³. These thumb-screws may be screwed down to close the slots i³. Thus when one or more of the nail-holders are out of use nails may be prevented from being fed thereto by screwing down the respective thumb-screws i¹⁴. The tubes g⁶ are made, preferably, of telescoping sections, so that the holders may be readily moved for the purpose of adjustment with reference to the bar I⁶.

Extending between the cheeks A' A² (see, for example, Fig. 27) are horizontal cross-bars A¹⁴ A¹⁵, provided in their upper sides with T-slots f. M and M' are outer braces or clenchers, and M² an inner brace or clencher. (See, for example, Figs. 7 and 27.) The braces or clenchers are in effect anvil members and comprise upright blocks or plates provided with nut-bolts f', the heads of which slide in the T-slots f. The braces or clenchers may be moved laterally and secured in position by tightening the nuts on the nut-bolts f'. The braces M M' are provided in their faces with shallow serrations f², forming clenching-surfaces, and the intermediate brace M² is

provided toward the top with similar serrations f² for the same purpose. On the brace M² (see Figs. 7 and 27) is a spring-catch f³, 70 for a purpose hereinafter described, and which may be adjusted to any desired height on the brace; also, upon the brace M² is a downward-extending guide-rod f⁴, which may be raised and lowered to adjust it to any desired height 75 upon the brace. The braces M M' M² collectively form an anvil, which takes the impact of the nail-drivers.

In the lower part of the machine and journaled at opposite ends in the cheeks A' A² is 80 a shaft K² in nearly the same plane as the shaft K. On the shaft K² are laterally-adjustable sprocket-wheels K³ and on the shaft K are laterally-adjustable sprocket-wheels K⁴. Extending over these sprocket-wheels are 85 feed-chains K⁵, each provided with box-end-engaging fingers K⁶, disposed as shown. On the shaft K², beyond the cheek A², is a sprocket-wheel K⁷, which is geared to a sprocket-wheel F⁸ on the shaft F by means of a drive-chain K⁸. 90 N is a fly-frame on a rock-shaft N', which is journaled at opposite ends in the lower edges of the cheeks A' A². The fly-frame is similar to those used in printing-machines generally. On the shaft N', beyond the cheek 95 A², is a disk N², eccentrically connected by means of a rod N³ with the shaft D² on the ram D, as shown most plainly in Figs. 2 and 9.

As a box end passes through the printing mechanism G, it is deposited upon the fly-frame N, which latter is then in the position shown, for example, in Fig. 27. Fastened upon the fly-frame and adjustable laterally is a guide N⁴, provided with clamps N⁵, (see Fig. 6,) whereby it may be secured in any desired position. The guide N⁴ is for the edge of the box end and operates to position it on the fly. The parts are so geared with relation to each other that when a box end has been deposited upon the fly the latter is swung 100 to a vertical position, carrying the upper edge of the box end beneath the lower end of the guide-rod f⁴ and the lower edge of the box end in the path of one set of fingers K⁶ on the feed-chains K⁵. The chains travel, moving 110 the box end upward between the anvil and vertical guide-arms P until it passes at its lower edge the catch f³ and is in position against the anvil for the nailing operation, as indicated in Fig. 34. The arms P press the 120 end firmly against the anvil. The blank Z, which is to form the sides, top, and bottom of the box, as before mentioned, is then passed by the operator over the outer anvil members, whereby its cleats at one end extend 125 over the edges of the box end. When this is done, the machine is started and nails are driven, as indicated in Figs. 31 and 32, and one box end thus fastened in place.

While the ram is moving backward after 130 the driving operation, the operator lifts off the box, being assisted at that time by the rise of another box end into position, when he turns the box, slips it at its other end portion

over the box end into position, and starts the machine again to complete the box, as shown in Fig. 27. When the operator presses the blank Z down upon the box end, the stop f^3 holds the latter firmly in place, so that it will not yield downward under the pressure.

While I prefer to construct my improvements throughout substantially as shown, it is to be understood that the printing mechanism may be dispensed with, if desired, and that the mechanisms may be variously modified in the matter of details of construction without departing from the spirit of my invention as defined by the claims.

15 What I claim as new, and desire to secure by Letters Patent, is—

1. In a box-nailing machine, the combination of a reciprocating ram, parallel series of nail-drivers mounted upon the ram, nail feeding and positioning devices, supported to co-operate with the nail-drivers, an anvil device having side faces against which the parts of the box are assembled and over which they are formed into the box shape, and having 20 anvil-faces in line with the nail-drivers against which the corner edges of the box abut when the nails are driven, substantially as and for the purpose set forth.

2. In a box-nailing machine, the combination of a reciprocating ram, two parallel series and a cross series of nail-drivers mounted upon the ram, nail feeding and positioning devices supported to co-operate with the nail-drivers, an anvil device having side faces 35 against which the parts of the box are assembled and over which they are formed into the box shape, and having anvil-faces, in line with the said parallel and cross series of nail-drivers, against which the corner edges of 40 the box abut when the nails are driven, substantially as and for the purpose set forth.

3. In a box-nailing machine, the combination of a reciprocating ram, series of nail-drivers carried by the ram and relatively adjustable thereon to conform to and operate 45 simultaneously against a plurality of box edges, nail feeding and positioning devices supported to co-operate with the said nail-drivers, an anvil device having side faces 50 against which the parts of the box are assembled and over which they are formed into the box shape, and having anvil-faces, in line with the nail-drivers, against which the corner edges of the box abut when the nails are 55 driven, substantially as and for the purpose set forth.

4. In a box-nailing machine, the combination of a reciprocating ram, series of nail-drivers carried by the ram and relatively adjustable thereon to conform to and operate 60 simultaneously against a plurality of box edges, nail feeding and positioning devices, a support upon which said devices are mounted and upon which they are relatively adjustable to position them with relation to the nail-drivers, an anvil device formed of relatively-adjustable members having side faces 65

against which the parts of the box are assembled and over which they are formed into the box shape, and having anvil-faces, in line 70 with the nail-drivers, against which the corner edges of the box abut when the nails are driven, substantially as and for the purpose set forth.

5. In a box-nailing machine, the combination of a reciprocating ram, series of nail-drivers carried by the ram and relatively adjustable thereon to conform to and operate simultaneously against a plurality of box edges, nail feeding and positioning devices, 80 a support upon which said devices are mounted and upon which they are relatively adjustable to position them with relation to the nail-drivers, an anvil device formed of relatively-adjustable members provided with serrated nail-clenching impact-faces, and forming a support having side faces against which the parts of the box are assembled and over which they are formed into the box shape, 85 said impact-faces being in line with the nail-drivers and forming a support against which the corner edges of the box abut when the nails are driven, substantially as and for the purpose set forth.

6. In a box-nailing machine, the combination with the drive-shaft, of a ram operatively connected with the drive-shaft to be reciprocated thereby, nail-drivers carried by the ram, nail feeding and positioning devices supported to co-operate with the nail-drivers, an anvil device having side faces against which the parts of the box are assembled and over which they are formed into the box shape, and having anvil-faces, in line with the nail-drivers, against which the corner edges of the box abut when the nails are driven, 90 means for positioning the box ends against the anvil device, comprising an endless carrier operatively geared to the said drive-shaft and provided with box-end engagers, and means for feeding the box ends to the carrier, substantially as and for the purpose set forth.

7. In a box-nailing machine, the combination with the drive-shaft, of a ram operatively connected with the drive-shaft to be reciprocated thereby, nail-drivers carried by the ram, nail feeding and positioning devices, a support upon which said devices are mounted and adjustable to position them with relation to the nail-drivers, an anvil device, positioning mechanism for box ends between the nail-position devices and the anvil device, comprising an endless carrier operatively geared to the said drive-shaft and provided with box-end-engaging means, and means for feeding box ends to the said carrier comprising an oscillating fly-frame actuated from the drive-shaft, substantially as and for the purpose set forth.

8. In a box nailing and printing machine, the combination with the drive-shaft, of a reciprocating ram operatively connected with the drive-shaft, nail-drivers carried by the

ram, nail feeding and positioning devices supported to coöperate with the nail-drivers, an anvil device having side faces against which the parts of the box are assembled and over which they are formed into the box shape, and having anvil-faces, in line with the nail-drivers, against which the corner edges of the box abut when the nails are driven, movable box-end engaging and positioning mechanism between the nail-positioning devices and the anvil device, a box-end-printing device, means for feeding the box ends to the printing device, and box-end-transferring mechanism movable between the printing device and the said box-end-positioning mechanism, all actuated from the said drive-shaft, substantially as and for the purpose set forth.

9. In a box nailing and printing machine, the combination with the drive-shaft, of a reciprocating ram operatively connected with the drive-shaft, nail-drivers carried by the ram, nail feeding and positioning devices, a support upon which said devices are mounted and positioned with relation to the nail-drivers, an anvil device, movable box-end engaging and positioning mechanism between the nail-positioning devices and the anvil device, a box-end-printing device comprising a printing-cylinder, means for feeding box ends to and through the printing device, and a fly-frame between the printing device and the said box-end-positioning mechanism, all operatively connected with the drive-shaft, to operate substantially as and for the purpose set forth.

10. In a box nailing and printing machine, the combination with the drive-shaft, of a reciprocating ram operatively connected with the drive-shaft, nail-drivers carried by the ram, nail feeding and positioning devices, a support upon which said devices are mounted and positioned with relation to the nail-drivers, an anvil device, movable box-end engaging and positioning mechanism between the nail-positioning devices and the anvil device, a box-end-printing device comprising cylinders actuated from the drive-shaft through which the box ends pass, a support for box ends, an endless carrier at said support actuated from the drive-shaft to feed the box ends one at a time from the support to

the printing device, and a fly-frame actuated from the drive-shaft to receive the box ends from the printing device and move them to the said positioning mechanism, substantially as and for the purpose set forth.

11. In a box-nailing machine, the combination with the nail-drivers and nail feeding and positioning devices supported to coöperate with the nail-drivers, of an anvil device having side faces against which the parts of the box are assembled and over which they are formed into the box shape, and having anvil-faces, in line with the nail-drivers, against which the corner edges of the box abut when the nails are driven, a box-end elevating and feeding carrier operating to move the box ends to the anvil device and discharge the box from the anvil device, and a resilient stop adjacent to the anvil upon which the box end rests in the nailing operation, substantially as and for the purpose set forth.

12. In a box-nailing machine, the combination with the main frame and constantly-rotating drive-shaft, of a normally stationary counter-shaft parallel with the drive-shaft, a ram eccentrically geared to said counter-shaft, a gear-wheel normally loose upon the counter-shaft in mesh with a gear upon the drive-shaft to rotate constantly, clutch mechanism between the counter-shaft and the rotating gear thereon, a second counter-shaft, a gear-wheel normally loose upon said second counter-shaft and rotated constantly from the drive-shaft, clutch mechanism between the second counter-shaft and its gear, box-end feeding and positioning mechanism operatively connected with the said second counter-shaft, means for operating the clutch upon the first counter-shaft to cause said shaft to be rotated and released by the gear-wheel thereon, and trip mechanism in the path of the ram and operatively connected with the clutch upon the second counter-shaft to make and release engagement between the second counter-shaft and its gear-wheel, all arranged to operate substantially as and for the purpose set forth.

FREDERICK P. ROSBACK.

In presence of—

J. H. LEE,
R. T. SPENCER.
